UNITED STATES PATENT OFFICE.

WILLIAM A. SMITH, OF ATHENS, PENNSYLVANIA, ASSIGNOR TO INGERSOLL-RAND COMPANY, OF JERSEY CITY, NEW JERSEY, A CORPORATION OF NEW JERSEY.

CHUCK FOR ROCK DRILLS.

Application filed October 10, 1925. Serial No. 61,825.

This invention relates to fluid actuated rock drills, of the hammer type, but more particularly to a chuck for said rock drills adapted to receive lugged steel.

5 The chuck is like that shown in my co-pending application, Serial No. 737,510, filed September 13, 1924, for rock drill.

The objects of the invention are to strengthen such chucks and prevent breakage due to the strains produced by the rotation of parts. Further objects are to provide ample bearings for the rotating parts of the chuck.

10 The invention is shown in one of its preferred forms in the accompanying drawing, which is a longitudinal sectional elevation partly broken away of so much of the rock drill as will serve to illustrate the invention.

15 The invention is shown as applied to a rock drill having rifle bar rotation and the rock drill comprises the cylinder A having the reciprocating piston B adapted to impart blows of impact to the drill steel C shown in this instance as a lugged steel 20 having the lugs D. Pressure fluid is supplied to the rock drill from the supply pipe E and the usual throttle valve is provided having the handle F. The automatic distribution valve in the valve chest G is indicated as being of the type shown in my 25 said copending application, Serial No. 737,510.

30 In accordance with this invention, the cylinder A is provided with an internal forward integral shoulder H and an external integral flange J intermediate the shoulder H and the front end K of the cylinder. A separate removable front cylinder washer L is located in the cylinder 35 rearwardly of the shoulder H and a chuck nut O is located in the cylinder forwardly of said shoulder H and adapted to abut against said shoulder. The piston B is provided with the forward fluted extension P 40 cooperating with the chuck nut O for rotation purposes.

45 A rotation sleeve Q is clutched to said chuck nut O at a point within the forward end of the cylinder as shown by the dotted lines indicating the clutch jaws R and this rotation sleeve has an external flange S adapted to abut against the front end K of the cylinder and is also provided with an internal shoulder T at its rearward end.

55 A chuck bushing U in said rotation sleeve Q abuts against the shoulder T, and a chuck key V is clutched to said rotation sleeve by the jaws W.

60 The front head X has a rearward enlarged portion Y formed with an enlarged bore within which the said external flange S on the rotation sleeve Q lies, and into which the forward end K of the cylinder extends, so that the rearward end a of the front head X bears against the external 65 flange J at the forward end of the cylinder. Sufficient clearance is provided between the shoulder b within the rearward end of the front head and the front end K of the cylinder to permit free rotation of the chuck 70 sleeve, any suitable means (not shown) being provided for oiling this portion of the chuck.

75 In accordance with this construction, the rotation sleeve Q has a bearing within and is guided by the integral forward end of the cylinder at the point c. The cylinder at this point is provided with the external flange J which affords a reinforcement and also forms a bearing for the rearward end 80 of the front head X. The longitudinal movement or play of the sleeve Q is limited between the shoulder b of the front head and the front end K of the cylinder and owing to the fact that the rearward enlarged 85 portion Y of the front head extends outside of the rotation sleeve flange S, the parts are reinforced against side strains at this point.

90 I claim:

95 In a fluid actuated rock drill of the hammer type having rifle bar rotation, the combination of a cylinder having an internal forward integral shoulder and an external integral flange intermediate said shoulder and the front end of the cylinder, a separate removable front cylinder washer rearwardly of said integral shoulder, a chuck nut in the cylinder forwardly of said shoulder adapted to abut against said shoulder, a reciprocating piston having a forward fluted extension 100 cooperating with said chuck nut, a rotation sleeve clutched to said chuck nut within the forward end of the cylinder and having an external flange adapted to abut against the front end of the cylinder and also provided with an internal shoulder at its rearward end, a chuck bushing in said 105

rotation sleeve abutting against said internal rotation sleeve shoulder, a chuck key clutched to the said rotation sleeve, and a front head having a rearward portion formed with an enlarged bore within which the said external flange on the rotation sleeve lies and into which the integral for-

ward end of the cylinder extends, said rearward portion of the front head bearing against the external flange on the cylinder. ¹⁰
In testimony whereof I have signed this specification.

WILLIAM A. SMITH.
